UNITED STATES PATENT OFFICE.

VICTOR STOLL, OF BROOKLYN, NEW YORK.

DENTAL TOOL.

1,227,687.

Specification of Letters Patent. Patented May 29, 1917.

Application filed September 6, 1916. Serial No. 113,622.

To all whom it may concern:

Be it known that I, VICTOR STOLL, a citizen of the United States of America, residing at Brooklyn, county of Kings, and State 5 of New York, have invented certain new and useful Improvements in Dental Tools, of which the following is a full, clear, and exact description.

This invention relates to dental tools using 10 retaining devices for casts and paralleling devices for the teeth to be added to a group or series already placed. The said invention consists in the construction and combination of devices hereinafter more particularly set 15 forth and claimed.

I will now proceed to describe my invention in detail, the essential features of which will be summarized in the appended claims, reference being had to the accompanying 20 drawings, forming part hereof; wherein—

Figure 1 is a side elevation of one embodiment of my invention, partly in section;

Fig. 2 is a sectional plan view thereof, the section being taken on a line 2—2 in 25 Fig. 1;

Fig. 3 is a front view thereof;

Fig. 4 is an enlarged sectional detail plan view of the supporting rod and clamp for the mandrel supporting arm, the section being taken on a line 4—4 in Fig. 1;

Fig. 5 is an enlarged vertical sectional detail view of the mandrel supporting arm, the section being taken on a line 5—5 in Fig. 1;

Fig. 6 is an enlarged top plan view of the 30 supporting box positioning carrier, the mandrel being shown in section;

Fig. 7 is a side view thereof;

Fig. 8 is a side view of a form of box or tube which my improved device is designed 40 to position;

Fig. 9 is a top plan view thereof;

Fig. 10 illustrates a modified form of means to engage the wax base of the group or set of teeth to be treated; and

Fig. 11 is a plan view illustrating a supporting box and plate carried thereby.

As herein embodied, my invention consists of a base portion 15 of any desired configuration, carrying a vertical post 16 for 50 supporting the positioning device 17. The positioning device 17 comprises a horizontally disposed beam or arm 18 carrying a clamping element consisting of a block 19, having an opening 20 therethrough, and a set-screw 21. The block 19 supports a vertical post 22 provided at its lower end with

a chuck 23 to engage and removably retain a mandrel 24. The post 22 is further provided with a transverse opening or slot 25 to slidably receive a transversely adjustable beam or caliper-arm 26. To the beam or caliper-arm 26, I slidably secure a block 27 carrying a chuck 28 for a mandrel 29, similar to the mandrel 24. These two vertical mandrels 22 and 29 are the paralleling rods 60 of the mechanism. The block 27 is secured in adjusted positions by a set-screw 30. To secure the horizontal arm 18 to the vertical post 16, I employ a clamp consisting of a split block 31 through which the rod 16 65 freely passes (see Figs. 4 and 5) one member of the block 31 being recessed at 32 (see Fig. 5) to receive the rod 18, said rod being flattened at 33 to prevent the rotation thereof. The rod 18 passes through an opening 70 75 in block 35, carrying a threaded spindle 36, said spindle passing through the split portion of the clamp-member or block 31. (See Fig. 5). To secure the block 31 and arm 18, in any position upon the vertical 80 post 16, the wing-nut 37 will be operated to draw the members of the split portion of the block 31 together, at the same time drawing the rod or arm 18 against the block 31. The positioning element 17 can be moved and 85 fastened in any vertical position on the post 16, as well as in any radial position. The rod 22 can be moved or adjusted vertically and held by the set-screw 21. It can also be rotatably adjusted and held by said set-screw 21. The caliper-arm 26 can be adjusted transversely of the axis of the vertical rod 22 and held by the set-screw 38. The block 27, carrying the chuck 28 for the mandrel 29, can be adjusted longitudinally 90 of the caliper-arm 26 and held by the set-screw 30. By the adjusting devices set forth above the interval between the paralleling rods 22 and 29 may be readily increased or diminished as required. Should I desire to 100 fit teeth in the space 39 in a cast 40 (Fig. 3) I would apply to the back of said set a layer of wax 41. To secure the set of teeth in position upon the upper surface 42 of the base 15, I provide same with recesses 43, into 105 which some of the wax will be forced when pressure is applied to the set of teeth. This downward pressure will force some of the wax into the recesses 43, thereby forming projections or teats 44 (Fig. 1) which will 110 act to hold the mass against movement during the box positioning operation. Further

- more, the mass can be removed and again accurately positioned. Instead of employing the recesses 43, I may employ pins 45 (Fig. 10) which will form recesses in the layer of 5 wax 41. After having positioned the set of teeth, or before, I apply to the carriers 46 on the mandrels 24 and 29 (see Figs. 6 and 7), the boxes or supports 47 for the plates 48 to which the added teeth are secured. 10 The boxes are slipped onto the carriers 46, as will be evident. Fig. 1 illustrates a box 47 mounted on its carrier. The boxes 47, as is obvious, are split tubes having wings. The cylindrical portion of the box receives 15 the cylindrical portion 49 of the plates 48 as shown in Fig. 11.

After the boxes are placed on the carriers, the positioning device is adjusted vertically and radially and the beam 26 or block 27 is 20 also adjusted transversely to position the boxes carried by the mandrels in place against the teeth selected to support them. When properly positioned, the boxes will be secured to the teeth by wax and the mandrels 25 and carriers raised to clear the boxes, which are of course left on the teeth. After the mandrels are withdrawn, the plates 48 are placed in the boxes and the artificial teeth secured thereto. Should I desire to position 30 but one box, the caliper-arm 26 can be removed.

By means of my improved positioning device, I am able to position the axes of the boxes 47 in an accurate vertical plane and in 35 parallelism with each other.

While the boxes 47 are carried by the teeth of the cast, the artificial teeth are applied to the plates carried by the box and fitted in the space 39. As the cast is an exact reproduction of the mouth, the fitted teeth plates 40 47 secured thereto and the boxes on the plates, will be removed from the cast and placed in the mouth for final securing while in this assembled condition.

45 What I claim as my invention is:
1. In a dental tool, in combination with a

vertical post a non-rotary horizontal arm adjustably secured to said post and vertical paralleling rods adjustably connected to said horizontal arm for varying the interval between said rods. 50

2. In a dental tool, an arm and a pair of paralleling rods, one of which is adjustable toward or from the other on said arm, in combination with means for suspending said 55 arm and rods and means for adjusting the position of said rods vertically, horizontally and to various angles in a horizontal plane, for insuring the accurate presentation of what is carried by said paralleling rods. 60

3. In a dental tool, a retainer for a cast, a vertical post supported over the same for vertical adjustment, it being also provided with means for its horizontal adjustment about a fixed point of support, a horizontal 65 arm slideable through said post and provided with means for clamping said arms at any point of such adjustment, a device slideable on said bar and adapted to be clamped at any desired point, said post and device each 70 carrying a paralleling rod.

4. In a dental tool, a pair of transversely slotted paralleling devices, in combination with an arm slideable through the slots of said devices, clamping means operating on 75 said arm to hold said devices at any desired interval from each other, and means for supporting said arm and paralleling devices for the purpose set forth.

5. In a dental tool, a pair of paralleling 80 devices, in combination with an arm, means for adjusting the interval between said devices on said arm, and means for supporting said arm and paralleling devices and adjusting them to any required position over a 85 cast.

Signed at New York city, N. Y., this 2
day of September, 1916.

VICTOR STOLL.
